UNITED STATES PATENT OFFICE.

PHILIP H. LETTRÉ, OF ATTLEBORO FALLS, MASSACHUSETTS.

TIE FASTENER.

Application filed July 23, 1925. Serial No. 45,656.

This invention relates to a combined cravat and cravat holder, the primary object of the invention being to provide a holder on which a cravat may be tied, and retained in such tied condition, the securing means being such as to hold the cravat in its proper position within the collar of the wearer.

An important object of the invention is the provision of means to insure against lateral movement of the holder while in use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view illustrating a holder and cravat tied in accordance with the present invention.

Figure 2 is an elevational view illustrating the cravat in a semi-tied position.

Figure 3 is a view illustrating the holder and disclosing the hollow collar button forming a part of the device.

Referring to the drawing in detail, the holder includes a curved body portion indicated by the reference character 5 which is formed preferably of flexible metal or the like, the same being curved as shown by Figure 2 of the drawing when in its normal condition, to the end that the device may conform to the curvature of the collar with which the device is used.

Extending inwardly from the body portion 5 and disposed at a point substantially intermediate the ends of the body portion is a retaining pin 6 which is adapted to be positioned within the hollow collar button 7

employed at the front of the shirt, the collar button acting to retain the collar in position in the usual and well known manner.

The cravat which is indicated by the reference character 8 is folded intermediate its ends, the central portion thereof being positioned at a point adjacent to the pin 6, the ends of the cravat being brought up and over the body portion 5 as shown by Figure 2. The ends are now forced downwardly under the loop 9 formed by folding the cravat and the ends are drawn until the cravat takes the form of a four-in-hand such as shown by Figure 1.

In this condition, the cravat is positioned in the usual place with respect to the collar and the curved ends of the body portion 5 are positioned under the folds of the collar with which the cravat is worn, the pin 6 having been positioned within the collar button forming a part of the device.

Thus it will be seen that due to this construction, the cravat is absolutely locked in position, the curved body portion acting to prevent outward movement of the cravat while the pin 6 absolutely insures against lateral movement thereof.

I claim:

In a device of the character described, a curved metal rod, a pin extending inwardly from the rod and disposed intermediate the ends of the rod, the inner end of said pin being disposed in spaced relation with a line connecting the ends of the rod, said rod adapted to support a tie wrapped around the rod and on opposite sides of the pin, said pin adapted to prevent lateral movement of the tie on the rod, and said pin adapted to be positioned in a hollow collar button to secure the rod in position.

In testimony that I claim the foregoing as my own, I have hereto affixed my signature.

PHILIP H. LETTRÉ.
